US00D488862S

(12) **United States Design Patent** (10) Patent No.: **US D488,862 S**
 McCalmon et al. (45) Date of Patent: ** Apr. 20, 2004

(54) **HANDPIECE FOR JET INJECTOR**

(75) Inventors: **Pat McCalmon**, Lenexa, KS (US);
Boris Smoliarov, Vorenezh (RU);
Mike Mathews, Lenexa, KS (US)

(73) Assignee: **Felton International, Inc.**, Lenexa, KS (US)

(**) Term: **14 Years**

(21) Appl. No.: **29/161,909**

(22) Filed: **Jun. 4, 2002**

(51) LOC (7) Cl. **24-02**

(52) U.S. Cl. **D24/113; D24/133; D24/146**

(58) Field of Search **D24/113, 114, D24/133, 146, 147, 143, 111; 604/68, 71, 70, 140, 27**

(56) **References Cited**

(74) Attorney, Agent, or Firm—Mayer Brown Rowe & Maw LLC; Joseph A. Mahoney; Christine M. Rebman

(57) **CLAIM**

The ornamental design for a handpiece for jet injector, as shown and described.

DESCRIPTION

FIG. 1 is a side view of the handpiece of the present invention.

FIG. 2 is a bottom perspective view of the handpiece of the present invention.

FIG. 3 is a side perspective view of the handpiece of the present invention; and,

FIG. 4 is a top perspective view of the handpiece of the present invention.

The broken lines included in the drawings depict environment and are not part of the claimed design.

1 Claim, 4 Drawing Sheets
